UNITED STATES PATENT OFFICE

121,689

DESIGN FOR A COMBINED DISPLAY STAND AND BOTTLES OF PERFUME

Victor Leff, New York, N. Y.

Application May 25, 1940, Serial No. 92,618

Term of patent 3½ years

To all whom it may concern:

Be it known that I, Victor Leff, a citizen of the United States of America, residing in the city of New York, county of New York, and State of New York, have invented a new, original, and ornamental Design for a Combined Display Stand and Bottles of Perfume, of which the following is a specification, reference being had to the accompanying drawing, forming part thereof.

The figure is a perspective view of a combined

display stand and bottles of perfume, showing my new design.

The opposite side of the article is the same as the side illustrated.

I claim:

The ornamental design for a combined display stand and bottles of perfume, substantially as shown and described.

VICTOR LEFF.
